THERMAL INSULATOR FOR A HOT AND COLD FOOD SERVICE CART

Lorance E. Sterns, Indianapolis, Ind., assignor, by mesne assignments, to J. Thomas Heckel, Jr., Indianapolis, Ind.

Filed Oct. 8, 1962, Ser. No. 72,012

Term of patent 14 years

(Cl. D81—1)

Fig. 1.

Fig. 2.

Fig. 3.

Fig. 4.

Fig. 5.

FIG. 1 is a left front perspective view of the thermal insulator for a hot and cold food service cart, showing my new design.

FIG. 2 is a top plan view thereof.

FIG. 3 is a bottom plan view thereof.

FIG. 4 is a front view thereof.

FIG. 5 is an elevational view of the side opposite that shown in FIG. 1.

I claim:

The ornamental design for a thermal insulator for a hot and cold food service cart, as shown.
